DESIGN FOR A COMBINED HAT AND SCARF

Lilly Daché, New York, N. Y.

Application March 29, 1937, Serial No. 68,456

Term of patent 3½ years

To all whom it may concern:

Be it known that I, Lilly Daché, a citizen of the United States, residing at No. 112 Central Park South, in the city, county, and State of New York, have invented a new, original, and ornamental Design for a Combined Hat and Scarf, of which the following is a specification, reference being had to the accompanying drawing, forming a part thereof.

I claim:

The ornamental design for a combined hat and scarf substantially as shown and described.

LILLY DACHÉ.
